REFRIGERATION APPARATUS

William Maxwell Saunders, Longmeadow, Mass., assignor to Westinghouse Electric & Manufacturing Company, East Pittsburgh, Pa., a corporation of Pennsylvania

Application November 23, 1938, Serial No. 241,939

11 Claims. (Cl. 62—89.5)

This invention relates to refrigerator cabinets and more especially to refrigerated display cases.

It is an object of this invention to provide a refrigerated display case in which dehydration of the foods displayed therein is minimized.

A further object of the invention is to provide a refrigerated cabinet of the type described having upper and lower compartments, each of which is maintained at a substantially uniform 10 temperature and the refrigeration of one of which may be materially reduced.

It is another object of my invention to provide a novel and useful arrangement of the cooling elements in a display case of the forced air circulation type.

These and other objects are effected by my invention as will be apparent from the following description and claims taken in connection with the accompanying drawings, forming a part of 20 this application, in which:

Fig. 1 is a vertical section of a refrigerator embodying the invention taken on the line I—I of Fig. 2 and with parts broken away for clearness; and,

Fig. 2 is a vertical section of the refrigerator taken on the line II—II of Fig. 1.

Referring now to the drawings, the reference numeral 10 represents a refrigerator cabinet having an upper compartment 11 and a lower compartment 12. A cooling unit 13 is disposed between the compartments 11 and 12 and is supported in a slightly inclined position on brackets 14. The cooling unit 13 comprises spaced strips of metal 15 through which a refrigerant carrying tube 16 is passed back and forth. A shelf 17 comprising spaced metal bars 18 is supported by pins 19 or bars running lengthwise immediately above the cooling unit 13, and metal pans 21 for the materials to be displayed are supported on the shelf 17. A drain baffle comprising a double row of angle bars 23 is secured in an inclined position by hooks 24 to the cooling unit 13 and conveys the moisture dripping from the unit towards the front wall of the refrigerator and permits it to drip into a trough 25. The trough 25 is provided with a pipe 26 through which the condensate drains into a water pan 27 in the bottom of the lower compartment of the refrigerator. The water pan 27 is provided with a drain pipe 28, the entrance opening 29 of which is elevated above the bottom of the pan 27 so that a portion of the water is retained in the pan 27 to humidify the air in the refrigerator. A perforated false bottom 31 for the lower compartment

12 is supported by inturned flanges 32 on the edges of the water pan 27.

Front walls 33 and rear walls 34 of the upper compartment 11 are sloped and the front wall 33 is provided with windows 35 through which customers can see the merchandise displayed on the shelf 17. Rear walls 34 and 36 of both the upper compartment 11 and the lower compartment 12 are provided with doors 37 and 38, the doors 37 of the upper compartment 11 being of the sliding, glass panel type.

In accordance with this invention, the air in the refrigerator is circulated to equalize the temperature in each compartment. The general direction of the air flow in the compartments 11 and 12 is preferably upward so that the air does not impinge directly upon the merchandise displayed on the pans 21. This reduces the dehydration of the merchandise.

The circulation of the air is established by 20 withdrawing air through a perforated conduit 42 in the top of the refrigerator and conducting it downwardly through a space between a false wall 43 and a side wall 44 of the refrigerator. The false side wall 43 has a portion cut out near its bottom, which opening is closed by a curved plate 46 to provide an enlargement in the air space for the fan 39 and the motor 41. A horizontal partition 47 is also provided in the space in line with the fan 39 to insure that the air 30 circulated by the fan 39 passes through the storage chambers 11 and 12 of the refrigerator. The air space in the side wall of the refrigerator has an opening connecting with the air space below the false bottom 31 of the lower refrigerator compartment 12 and the air enters the lower compartment 12 through perforations 48 in the false bottom 31.

A second cooling unit 49, of similar construction to the cooling unit 13, is located near the front wall of the refrigerator and is supported on brackets 51 above the trough 25. A tube 52 of the second cooling unit 49 is connected in series with the tube 16 of the cooling unit 13 and ends 53 of the combined tube are brought out 45 through the walls of the refrigerator for connection to a refrigerant supply unit (not shown). The function of the second cooling unit 49 is to aid in cooling the lower compartment 12 which otherwise may be too warm since it receives the 50 warmest air of the upper compartment 11 which air is further warmed in the air duct adjacent the false side wall 43 and the air duct below the false bottom 31. The circulation of the air through the storage compartments 11 and 12 is

relatively slow, its speed being, for example, at the rate of six to seven feet per minute.

This slow rate of air circulation reduces the dehydration of the food exposed to it and also permits the second cooling unit 49 to set up its own individual convectional air current in the lower chamber 12, the direction of flow being downwardly adjacent the unit 49. The establishment of this convectional air current is further aided by a baffle 54 adjacent the unit 49 which separates the downward convectional air flow from the general upward air flow in the storage compartment 12. To further aid the convectional air flow, the perforations 48 in the false bottom 31 are provided only in the front portion away from the second cooling unit 49. This sets up an eddy current above the imperforated portion of the false bottom 31 which coincides substantially with the path of the convectional air current set up by the second cooling unit 49 and increases the speed of circulation of this current.

As shown by the arrows in Fig. 1, the downward convectional air flow commingles at the bottom of the lower chamber 12 with the general upward air flow in this chamber and aids in cooling the lower chamber. This commingling action is effected by the ejector action of the jets of air flowing through the perforations 48 in the false bottom 31, and results in cooling the air in the lower chamber 12 to substantially the same, or if desired, a lower temperature than the air in the upper compartment 11.

The upper compartment 11 is intended for displaying the merchandise to the customers and the lower compartment 12 for storing the reserve supply of merchandise. At night and during holidays the merchandise in the upper compartment 11 may be removed and placed in the lower compartment 12 and the motor 41 stopped. This will substantially reduce the refrigeration of the upper compartment 11 and reduce the cost of operating the refrigerator.

It will be apparent that this invention provides a refrigerator in which the temperature is uniform in each compartment and in which the dehydration of the food displayed therein is reduced to a minimum. It also provides a display case having an upper compartment, the refrigeration of which may be substantially reduced to reduce the cost of operation.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

60 What I claim is:

1. In a display refrigerator, the combination of a cabinet, a relatively flat and substantially horizontal cooling unit therein dividing said cabinet into upper and lower food storage compartments, said cooling unit having closely spaced air passages substantially throughout its area, said cooling unit cooperating with the walls of said cabinet to prevent substantial quantities of air from passing around the edges of said cooling unit directly from one compartment to the other, means associated with said cabinet for propelling air, means for directing air from an extended area adjacent the upper portion of said upper compartment to said air propelling means, means for discharging air from said air propelling means over

an extended area into the lower compartment and remote from said cooling unit, the air thereafter passing through the air passages of said cooling unit to said upper compartment, whereby said air is cooled substantially uniformly as it passes through the cooling unit. 5

2. In a display refrigerator, the combination of means forming a cabinet, means for cooling said cabinet comprising a relatively large, flat, and substantially horizontal cooling unit therein defining storage compartments in said cabinet above and below said cooling unit, said cooling unit having closely spaced air passages throughout a substantial area thereof, means for preventing substantial quantities of air from passing around the edges of said cooling unit directly from one compartment to the other, means associated with said cabinet for propelling air, means for directing air from an extended area adjacent the upper portion of said cabinet to said air propelling means, means for discharging air from said air propelling means over an extended area into the lower compartment remote from said cooling unit, the air thereafter passing through the air passages of said cooling unit to said upper compartment, whereby said air is cooled substantially uniformly and substantially throughout the entire area of said cooling unit. 10

3. In a display refrigerator, the combination of means forming a cabinet, means for cooling

30 said cabinet comprising a relatively large, flat, and substantially horizontal cooling unit therein defining storage compartments in said cabinet above and below said cooling unit, said cooling unit having closely spaced air passages throughout a substantial area thereof, means for preventing substantial quantities of air from passing around the edges of said cooling unit directly from one compartment to the other, means associated with said cabinet for propelling air, 35 means for directing air from an extended area adjacent the upper portion of said cabinet to said air propelling means, means for discharging air from said air propelling means over an extended area into the lower compartment remote 40 from said cooling unit, the air thereafter passing through the air passages of said cooling unit to said upper compartment, said air propelling means moving the air through said compartments at a speed of about six feet per minute and substantially uniformly through the air passages of said cooling unit to cool the air uniformly there- 45 in. 50

4. In a display refrigerator, the combination of a cabinet, a relatively flat and substantially horizontal cooling unit therein dividing said cabinet into upper and lower food storage compartments, said cooling unit having closely spaced air passages substantially throughout its area, said cooling unit cooperating with the walls of said cabinet to prevent substantial quantities of air from passing around the edges of said cooling unit directly from one compartment to the other, a drip collector below said cooling unit, said drip collector comprising spaced-apart troughs, means associated with said cabinet for propelling air, means for directing air from an extended area adjacent the upper portion of said upper compartment to said air propelling means, means for discharging air from said air propelling means over an extended area into the lower compartment remote from said cooling unit, the air thereafter passing through the drip collector and the cooling unit to said upper compartment, whereby said 55 60 65 70 75

air is cooled substantially uniformly as it passes through the cooling unit.

5. In a display refrigerator, the combination of a cabinet, a relatively flat and substantially horizontal cooling unit therein dividing said cabinet into upper and lower food storage compartments, said cooling unit having closely spaced air passages substantially throughout its area, said cooling unit cooperating with the walls of said cabinet 10 to prevent substantial quantities of air from passing around the edges of said cooling unit directly from one compartment to the other, a drip collector associated with the cooling unit, a pan in the bottom of the lower compartment, means 15 for conducting the condensate from the drip collector to the pan, means associated with said cabinet for propelling air, means for directing air from an extended area adjacent the upper portion of said upper compartment to said air propelling means, means for discharging air from said air propelling means 20 over an extended area into the lower compartment remote from both said main cooling unit and said auxiliary cooling unit, the air thereafter dividing, a portion thereof passing directly through the main cooling unit and another portion thereof 25 passing through said auxiliary cooling unit and thereafter commingling with the air entering said lower compartment.

6. In a display refrigerator, the combination of a cabinet, a relatively flat and substantially horizontal cooling unit therein dividing said cabinet into upper and lower food storage compartments, said cooling unit having closely spaced air passages substantially throughout its area, said cooling unit cooperating with the walls of said cabinet 30 to prevent substantial quantities of air from passing around the edges of said cooling unit directly from one compartment to the other, means associated with said cabinet for propelling air, means for rendering said air propelling means 35 inactive, means for directing air from an extended area adjacent the upper portion of said upper compartment to said air propelling means, means for discharging air from said air propelling means over an extended area into the lower compartment remote from said cooling unit, the air thereafter 40 passing uniformly through the air passages of said cooling unit to said upper compartment to cool said air substantially uniformly, the refrigeration of the upper compartment being substantially reduced when said air propelling means 45 is rendered inactive.

7. In a display refrigerator, the combination of means forming a cabinet, means for cooling said cabinet comprising a relatively large, flat, and substantially horizontal cooling unit therein defining storage compartments above and below said cooling unit, said cooling unit having closely spaced air passages throughout a substantial area thereof, means for preventing substantial quantities 50 of air from passing around the edges of said cooling unit directly from one compartment to the other, means associated with said cabinet for propelling air, means for directing air from an extended area adjacent the upper portion of said cabinet to said air propelling means, means for discharging air from said air propelling means over an extended area into the lower compartment remote from said cooling unit, the air thereafter 55 passing through the air passages of said cooling unit to said upper compartment and an auxiliary cooling unit in the lower compartment, the air being cooled substantially uniformly on its passage through said first-named cooling unit.

8. In a display refrigerator, the combination of means forming a cabinet, means for cooling said

cabinet comprising a relatively large, flat, and substantially horizontal main cooling unit therein defining storage compartments in said cabinet above and below said main cooling unit, said main cooling unit having closely spaced air passages throughout a substantial area thereof, means for preventing substantial quantities of air from passing around the edges of said main cooling unit directly from one compartment to the other, an auxiliary cooling unit in the lower 10 compartment, means associated with said cabinet for propelling air, means for directing air from an extended area adjacent the upper portion of said cabinet to said air propelling means, means for discharging air from said air propelling means 15 over an extended area into the lower compartment remote from both said main cooling unit and said auxiliary cooling unit, the air thereafter dividing, a portion thereof passing directly through the main cooling unit and another portion thereof 20 passing through said auxiliary cooling unit and thereafter commingling with the air entering said lower compartment.

9. In a display refrigerator, the combination of means forming a cabinet, means for cooling 25 said cabinet comprising a relatively large, flat, and substantially horizontal main cooling unit therein defining storage compartments in said cabinet above and below said main cooling unit, said main cooling unit having closely spaced air passages throughout a substantial area thereof, means for preventing substantial quantities of air from passing around the edges of said main cooling unit directly from one compartment to the other, an auxiliary cooling unit in said lower 30 compartment adjacent one side thereof, a baffle adjacent said auxiliary cooling unit, means for directing air from an extended area adjacent the upper portion of said cabinet to said air propelling means, means for discharging air from 35 said air propelling means over an extended area into the lower compartment remote from said main cooling unit and said auxiliary cooling unit, the air thereafter dividing and the larger portion of said air passing through said main cooling 40 unit and a smaller portion of said air circulating over said baffle and through said secondary cooling unit, said smaller portion of air thereafter 45 commingling with the air entering the lower compartment.

10. In a display refrigerator, the combination of a cabinet, a relatively flat and substantially horizontal main cooling unit therein dividing said cabinet into an upper and lower storage compartment, the edges of said cooling unit cooperating with the cabinet to prevent substantial quantities of air passing from one compartment directly to the other around the edges of said cooling unit, an auxiliary cooling unit in said lower compartment, a false bottom in said lower compartment 50 having spaced-apart openings therein over a substantial area remote from said secondary cooling unit, means associated with said cabinet for propelling air, means for directing air from an extended area at the upper portion of said upper compartment to said air propelling means, and means for discharging the air from said propelling means into said lower compartment through the openings in the false bottom thereof towards the cooling unit to produce an ejector 55 action which draws air downwardly through said auxiliary cooling unit and commingles it with the air issuing through said openings.

11. In a refrigerator, the combination of a cabinet, a main cooling unit therein defining stor- 75

- age compartments on two sides thereof, one of said compartments having openings in a wall remote from said cooling unit, means for withdrawing air from the other compartment at a location remote from the cooling unit and passing it through said openings towards the main cooling unit, and an auxiliary cooling unit in the compartment containing said openings and to one

side of the air stream issuing therefrom, whereby said air stream effects an ejector action which withdraws air from adjacent the auxiliary cooling unit and commingles it with the air issuing from said openings to additionally cool said last-named compartment.

WILLIAM MAXWELL SAUNDERS.
